UNITED STATES PATENT OFFICE.

FRANCIS STANHOPE PITT-TAYLOR, OF BLACKPOOL, ENGLAND.

CONCERTINA.

Application filed October 2, 1923, Serial No. 663,191, and in Great Britain October 3, 1922.

This invention relates to improvements in the keyboards of concertinas in which the keyboards are particularly adapted to the hands, the one to the one hand, and the other 5 to the other hand of the player, the keys of each keyboard being grouped in six parallel rows perpendicular to the straight line of the handrail, the keys in the body of the keyboard forming transverse line of six different-number keys, at least four of which form 10 a straight-transverse line of keys parallel with the line of the handrail, so that sometimes there may be two keys half a key-width above or below this line, the twelve different 15 notes of each octave being sounded by a pair of semi-octave-angular-transverse sets of six keys which are distributed over three straight-transverse lines of six keys, so that any straight-transverse line of six keys 20 contains portions of three semi-octave-angular-transverse sets of six keys, whilst the order of the notes sounded of each octave is that of a regular chromatic scale, one semi-octave-angular-transverse set of every pair of six 25 keys sounding the notes A, A sharp, B, C, C sharp, and D, and the other semi-octave-angular-transverse set of every pair of six keys sounding the notes D sharp, E, F, F sharp, G, and G sharp. By these improvements the 30 task of playing the concertina especially by the little and ring fingers is greatly facilitated.

In order that the several parts of my said invention may be easily and clearly understood, they are illustrated in the accompanying drawings, Figures 1, 3, 5, 7, 9, and 11, which show the keyboard on the right hand side of the concertina, whilst Figures 2, 4, 6, 8, 10, and 12, show that on the left hand 40 side of the instrument.

Figures 1, 2, 3, 4, 5, 7, 9, and 11 show 36 keys arranged in six different-number straight-transverse or angular-transverse rows of six keys, the keys being differently 45 numbered from the left edge in a straight or angular line across the keyboard, whilst Figures 6, 8, 10, and 12 show 30 keys arranged in five different-number angular-transverse rows of six keys.

50 In Figures 5 and 6 the line HH divides the keyboard into two sets of three keys in each set.

The compass shown in Figures 1, 3, 5, 7, 9, and 11 extends from A on the second leger 55 line below the line of the treble staff to G sharp on the fourth leger line above the line

of the same staff in Figures 1, 5, 7, 9, and 11, and to G sharp in the first space above the line of the same staff in Figure 3; or from A in the fourth octave to G sharp in the sixth 60 octave, or G sharp in the fifth octave of a pianoforte keyboard.

The compass shown in Figures 2, 4, 6, 8, 10, and 12, extends from A in Figure 10 on the third line below the line of the bass staff, 65 from D sharp in Figures 2, 6, 8, and 12 in the second space below the line of the bass staff, and from A in Figure 4 in the first space of the bass staff to D in Figure 10 in the second space above the line of the same staff, to G 70 sharp in Figures 4, 6, 8, and 12 on the third leger line above the line of the same staff, and to D in Figure 2 on the fifth leger line above the line of the same staff; or from A or D sharp in the second octave, or from A 75 in the third octave to D or G sharp in the fourth octave or to D in the fifth octave of a pianoforte keyboard.

In Figures 1 and 2 the keys as semi-octave note-sounders run straight across the board. 80 The lines MM which cut off three keys in these figures, in Figure 3 cut off three keys belonging to the sixth octave, and in Figure 4 to the fifth octave. Also the lines OO which cut off nine keys in Figures 1 and 2, 85 cut off nine keys belonging to the third octave in Figure 3, and to the second octave in Figure 4. Since an octave really includes thirteen notes, eight diatonic and five chromatic, and the eighth note of the diatonics, 90 or the thirteenth note is also the first note of the succeeding octave, octave marked 3A to 3G sharp really included the note marked 4A, and octave 4A to 4G sharp the note marked 5A. Consequently, there are two 95 complete octaves in each of the Figures 3 and 4 when we remember to include the notes marked 5A and 6A.

Figures 7 and 8 illustrate the finger-length position of my former patent, Pitt-Taylor, 100 U. S. A., No. 1,417,107, patented May 23, 1922, of which this invention is an improvement.

The figures have headings which are placed above the keys which not only distinguish the fingers which sound them most easily, but number them from the left edge of the keyboard with the numbers I to VI placed above the finger labels. All the keys placed one above the other from the bottom 105 to the top of the figures where there is a number constitute a same-number row so

that there are six same-number rows numbered I to VI.

I do not confine my patent to the number of keys shown in the figures, for a concertina 5 of lesser or greater compass can be constructed in the same manner if desired.

I will now consider in further detail the characteristic features of this invention.

The keyboards of Figures 5 and 6 can be 10 divided by the line HH into two parts, one containing the same-number rows IV, V, and VI. The same-number rows I, II, and III in Figure 5, and rows IV, V, and VI in Figure 6 are sounded by the middle and 15 index fingers and so are termed the MIF or middle-index fingers set. These keys form transverse rows of different-number keys YY, parallel to one another, which slope upwards to the right on the right side 20 and to the left on the left side thus forming an angle with the line of the handrail. The same-number rows I, II, and III, in Figure 6, and rows IV, V, and VI in Figure 5 are sounded by the ring and little fingers 25 and so are termed the RLF or ring-little fingers set. These keys in Figures 7 and 8 form lines XX which are parallel with the lines YY, but a slope which suits the increased length of the middle over the index 30 finger cannot possibly suit the reversed condition, the decreased length of the little finger under the ring finger. In order to adapt these keys to the hand of the player, in Figures 5, 6, 9, and 10 they are placed in 35 straight lines NN, NN1, NN2, NN3 parallel with the line of the handrail HR, thus enabling the little finger to sound the LFK or little finger key and the OLFK or outer little finger key more easily than before. 40 The three keys of the RLF set through the line NN are seen to be in a line with the IFK or index finger key of the MIF set, the MFK or middle finger key being only half a key-width above and the OIFK or outer index finger key being only half a key-width below 45 this line NN. This contrivance is not only a modification of the invention illustrated in Figures 7 and 8, but also of that shown in Figures 1, 2, 3, and 4, so that the construction 50 of the keyboard in respect of this improvement is greatly simplified, for no angles need to be measured or considered in setting out the position of the keys.

According to the compass, and therefore 55 to the number of octaves required, a series of parallel straight lines parallel with the handrail, and a suitable distance apart, about two key-widths, in number including two for each octave and two extra for the keyboard, like lines of print, are first drawn. These lines are divided at six points at suitable distances apart by six perpendicular 60 lines, and each intersection represents a possible key. On the right side with the compasses a circle is drawn the width of a key.

whose centre is placed on the sixth intersection of the last or bottom row, and similar circles are drawn at the fifth and sixth intersections of the penultimate row, and at the second and fourth intersections of all the rows above, and at the fifth of all the rows above except the first, and at the sixth of all the rows above except the first and second, and half a key-width below the first intersection of all the rows above, and half a key-width above the third intersection of all the rows above. If in the above description, the word "first" be substituted for the word "sixth", the word "second" for "fifth", "third" for "fourth", "fourth" for "third", "fifth" for "second", and "sixth" for "first", it applies exactly to the left side, and so from this plan both keyboards can be easily constructed. It will be noted that the right side, as shown in Figures 1, 3, 5, 7, 9, and 11 is the reverse of the left hand side shown in Figures 2, 4, 6, 8, 10, and 12. This reversal is necessary in order that the keyboards should be particularly adapted to each hand of the player.

In the modification illustrated in Figures 11 and 12 the circle is drawn at the third intersection of all the rows above on the right hand side and at the fourth on the left hand side; and in that illustrated in Figures 3 and 4 at the first intersection of all the rows above on the right hand side and at the sixth on the left hand side as well.

The keyboards seen in Figures 1 and 2 differ from the other figures for clarity of description by having the length-of-fingers difference in the position of the keys eliminated. Counting the rows upwards, the first two different-number rows of six keys of Figure 1, and the second and third different-number rows of six keys of Figure 2, and the keys of every succeeding pair of rows in both figures are able to sound when pressed the naturals and chromatics of one octave beginning with A forming a series of 100 regular complete chromatic pianoforte scales which progress from right to left on the right side, and from left to right on the left side. The notes sounded in the first different-number row of any pair by its 105 keys are A, A sharp, B, C, C sharp, and D, and the notes sounded in the second different-number row of any pair by its keys are D sharp, E, F, F sharp, G, and G sharp. The chromatic notes are therefore placed in 110 their proper position with reference to their appropriate naturals, the tones, the sharps being placed in front of and the flats immediately behind their appropriate tones. By having the first alphabetically named note 115 A sounded by the first key in each pair of different-number rows, the octave beginning therewith is completely contained in two rows of keys, which is true of no other regular order. This regular order fulfills the 120

requirements of consistency in placing "first things first," first in placing A first, and first in placing the order of the chromatic scale on the left side to progress from left 5 to right which is the pianoforte order and the alphabetical order, and by having the right hand to reverse the pianoforte order but not the alphabetical order the same-named finger on either side is able to play 10 the same-named note of similar in some cases, or of lower or higher pitch in other cases with equal facility.

Since the fingers are not all equally endowed with muscular power and in consequence 15 the index and middle finger pair are superior to the ring and little finger pair in their muscular endowments, this keyboard is adapted to the construction of the hand by having three chromatic notes to be sounded 20 by the better endowed pair, and only two by the lesser endowed pair. For F sharp, C sharp, and G sharp are sounded by the index and middle finger pair, and B flat and E flat by the little and ring finger pair.

25 It will be observed in Figure 4 that the keys as semi-octave note-sounders form an angle whose apex is at the RFK, one limb sloping upwards from the OLFK of the first row Z1, numbering the rows from below upwards, to the RFK of the third row shown by the line passing through or connecting the note-sounders 3A, 3A sharp, and 3B, and the other limb shown by the line passing through or connecting the note-sounders 3B, 3C, 3C sharp, and 3D running straight across the board parallel with the handrail to the OIFK of the sixth row N1. This angle Z13BN1 isolates three keys, two of which 3D sharp and 3E belong to the 30 next semi-octave row above, and one 4A which is the octave of 3A, and also the first note of the octave above. The straight transverse row NN1 is thus seen to be compounded of parts of three semi-octave- 35 angular-transverse rows, the OLFK sounding the last note 4A of the octave, the LFK sounding a note 3E belonging to the upper part of the octave, and the remaining four keys sounding the notes 3B, 3C, 3C sharp 40 and 3D belonging to the first part of the octave. These three semi-octave-angular-transverse rows Z1N1, Z2N2 and Z3N3 seen in Figures 3, 4, 9, 10, 11, and 12 produce a very characteristic feature when the keyboard 45 is strictly limited to the keys enclosed between the lines MM and OO in Figures 1, 2, 3, and 4. Omitting Figures 1 and 2, the keyboards illustrated in the other figures are constructed, beginning with a note-sounder or key which sounds the note A and ending with the note-sounder or key which sounds the subtonic G sharp, so that the twelve different notes of each octave are contained in two rows of six keys, half in 50 one row and the other half in the other

row. At the same time, the keys of each pair or semi-part-octave-angular-transverse row are distributed over three straight-transverse rows, the first key seen in Figure 10 2A being placed in the first straight-transverse row marked N—NO1, the second key 2A sharp in the second straight-transverse row N—NO2, and the rest of the keys 2B, 2C, 2C sharp, and 2D of the semi-pair row in the third straight-transverse row N—N1, with the result that any straight-transverse row of six keys contains keys belonging to three semi-pair rows, so that, for example, row N—N1, with its first key 3A being the first key of one angular row Z3—3B—N3, the third of that series of three angular rows, the second key 2E being the second key of the second Z2—2F—N2 of that series of three angular rows, and the third 2B, fourth 2C, fifth 2C sharp, and sixth 2D keys belonging to the first Z1—2b—N1 of that series of three angular rows. The keys of each semi-pair row are then divided into three parts, the first two parts consisting of one key each, and the third part being the four keys which are the remainder of the semi-pair row. Consequently, in a keyboard rigidly confined to semi-pair rows as in Figures 9, 10, 11, and 12, the top row must consist of the four 55 keys which are the third part of the first semi-pair row counting the rows from above downwards, whilst the second row must consist of the five keys which include the second part of the first semi-pair row together with the third part of the second semi-pair row, the third row consisting of the first part of the first semi-pair row, the second part of the second semi-pair row, and the third part of the third semi-pair row. The 60 body of the keyboard consists of transverse rows constructed similarly to the third row in number two less than the number of semi-pair rows, the penultimate row consisting of the first part of the penultimate semi-pair row and the second part of the last semi-pair row containing two keys only, and the last row consisting of the first part of the last semi-pair row containing one key only. In Figures 3 and 4 the two top and 65 the two bottom rows are filled up with keys belonging to other semi-pair rows, so that the block of rows all having six keys is formed of complete and partial semi-pair rows. Omitting the keys separated by the 70 lines MM and OO in Figures 3 and 4, in these figures and Figures 9, 10, 11 and 12, the first key on the left side and the sixth key on the right side may, belonging to the first part of the first angular-transverse semi-part-octave row, numbering the rows from below upwards, sound the note A, and belonging to the first part of the second angular-transverse-semi-part octave row sound the note D sharp, and likewise for 75 80 85 90 95 100 105 110 115 120 125 130

every pair of such angular rows, the second key on the left side and the fifth key on the right side may, belonging to the second part of the first angular-transverse-semi-part-octave row and situated in the second straight-transverse row, sound the note A sharp, and belonging to the second part of the second angular-transverse-semi-part-octave row, and situated in the third straight-transverse row, sound the note E, and likewise for every pair of such rows, and the third, fourth, fifth, and sixth keys on the right side may, belonging to the third part of the first angular-transverse-semi-part-octave row, and situated in the third straight-transverse row, sound the notes B, C, C sharp, and D, and belonging to the third part of the second angular-transverse-semi-part-octave row, and situated in the fourth straight-transverse row, sound the notes F, F sharp, G, and G sharp, and likewise for every pair of such rows, so that every alternate row contains notes of the same name and in the same position which only differ when they do differ by belonging to octaves of higher or lower position in the treble or bass.

The great advantage of this construction whereby a semi-part-octave row of six keys is distributed over three straight-transverse rows of keys thus forming an angular-transverse-semi-part-octave row, is that in the body of the keyboard the angular-transverse-semi-part-octave rows are hidden or masked, and the straight-transverse rows are objective and apparent, the keys being adapted to fulfill two purposes, one, to fit the different length of the fingers when playing notes in one semi-octave or octave, and two, to fit the necessity of the easiest play in a perpendicular direction, or up and down the keyboard from one octave to another.

The straight-transverse row of keys is straight throughout its length in Figures 3 and 4, but in Figures 11 and 12 the OIFK is set half a key-width lower, and in Figures 5, 6, 9, and 10 the MFK is set half a key-width higher as well.

50 I claim:

1. A concertina having two chromatic keyboards, one keyboard particularly adapted to one hand, the other keyboard to the other hand of the player, having its keys grouped in parallel rows parallel to the handrail, the rows being placed one above the other so as to form six lines of keys which are perpendicular to the straight line of the handrail, each transverse row in the body of the keyboard having six keys, whilst the rows at the extremities, the top two and the bottom two rows, may be of less plurality of keys, so that the top row may have the first four keys only on the right side and the last 65 four keys only on the left side, the second

row from the top may have the first five keys only on the right side, and the last five keys only on the left side, the penultimate row may have the last two keys only on the right side and the first two keys only on the left side, and the last row may have the last key only on the right side and the first key only on the left side. 70

2. In a concertina as claimed in claim 1 the first key of each row being half a key-width below the straight line formed by the remaining keys on the right side, numbering the keys from the left edge of the key-board, and the sixth key of each row being half a key-width below the straight line 80 formed by the remaining keys on the left side.

3. In a concertina as claimed in claim 1 the first key in each row being half a key-width below and the third key being half a key-width above the straight line formed by the second, fourth, fifth, and sixth keys on the right side, numbering the keys from the left edge of the key-board, and the fourth key in each row being half a key-width above and the sixth key being half a key-width below the straight line formed by the first, second, third, and fifth keys on the left side. 85

4. A concertina keyboard having its keys placed one above the other so as to form six lines of keys which are perpendicular to the straight line of the handrail, each transverse row in the body of the keyboard having six keys, with the keys of every pair of rows of six being able to sound when pressed the naturals and chromatics of the A commencing in one of the two rows and D sharp commencing in the other of the two rows complete regular chromatic scale of one 100 octave as in the pianoforte, sounding in the one row the notes A, A sharp, B, C, C sharp, and D, and in the other row the notes D sharp, E, F, F sharp, G, and G sharp: every alternate row having keys which sound naturals or chromatics of the same name and in the same position that only differ from each other when they do differ by being in octaves of lower or higher pitch. 110

5. A concertina having two chromatic keyboards, one for each hand of the player, each keyboard having its keys placed one above the other so as to form six lines of keys which are perpendicular to the straight line of the handrail, each transverse row in the body of the keyboards having six keys, with the keys of every pair of rows of six of each keyboard being able to sound when pressed the naturals and the chromatics of the A commencing in one of the two rows and D sharp commencing in the other of the two rows complete regular chromatic scale of one octave as in the pianoforte, sounding in the one row the notes A, A sharp, B, C, C sharp, and D, and in the 120 125 130

and belonging to the third part of the second angular-transverse-semi-part-octave row, and situated in the fourth transverse row, sound the notes F, F sharp, G, and G sharp, and likewise for every pair of such rows, so that every alternate row contains notes of the same name and in the same po-

sition which only differ when they do differ by belonging to octaves of higher or lower position in the treble or bass.

Signed at 106, Bloomfield Road, Blackpool, in the county of Lancaster, England, this sixteenth day of December 1926.

FRANCIS STANHOPE PITT-TAYLOR, M. B., Ch. B.
